FLASHLIGHT CASING

Rene Marcel Angibaud, Vernon, Eure, France, assignor to Societe Les Piles Wonder, Saint-Ouen, Seine-Saint-Denis, France

Filed Feb. 6, 1970, Ser. No. 21,319

Term of patent 14 years

Int. Cl. D26—04

U.S. Cl. D48—24

FIG. 1 is a front perspective view of a flashlight casing showing my new design;

FIG. 2 is a side elevational view thereof;

FIG. 3 is a front view thereof;

FIG. 4 is a rear view thereof; and

FIG. 5 is a sectional view taken on line 5—5 of FIG. 3, a portion of the casing being omitted for convenience of illustration.

I claim:

The ornamental design for a flashlight casing, as shown.
